DISTRIBUTING AND ASSEMBLING MACHINE

Robert S. Wentworth, Mamaroneck, N. Y.

Application October 8, 1941, Serial No. 414,044

11 Claims. (Cl. 214—11)

My invention relates to improvements to machines for distributing cards, sheets, envelopes or similar objects and for collating sheets of printed matter and more particularly a machine and a method of control which combines the two functions of distributing and collating in one machine.

One object of my invention is to provide a machine in which a very large number of receptacles for the objects to be distributed or collated may be provided in a minimum of space. This I accomplish by providing several rows of receptacles, one above the other, in tiers, to any desired height, from two to ten or even more.

Another object of the invention is to provide a machine in which a maximum of space is made available for the reception of distributed cards or sheets and as little space as possible is devoted to passages through which the distributed material passes on its way to the receptacles. This is accomplished by a novel arrangement for guiding the cards or sheets through very narrow passages defined by very slender wires.

Another object of the invention is to provide a machine which will occupy a minimum of floor space in relation to the number of delivery stations or receptacles served.

Other objects and advantages of the invention will be apparent from the following description or may be learned by the operation of the machine.

Previous machines of this general class for distributing cards, sheets or the like, require that the card sheet or other objects to be distributed have a distinctive or characteristic mark or mutilation or indicia, such as one or more punched holes which, by reason of their specific location on the card, permit electrical contacts to occur which serve to control the mechanism which carries the card to its predetermined destination, usually a receptacle.

In the previous machines it is the practice to provide each individual card with its own means for controlling the action of the sorting mechanism. It is one of the characteristics of the machine of the present invention that it utilizes a separate master control card which carries the necessary indicia or perforations by means of which the successive cards or sheets are guided to their destinations. The cards or sheets may be identical and carry no indicia, punchings or deformations. Each successive card or sheet fed to the machine will be picked up, carried to and deposited in the receptacle for which the master

control card had been provided with a corresponding indicia or perforation.

A machine in accordance with the present invention serves many useful purposes. For example, a statistical organization distributing periodic reports on any current subject to a large number of customers, each of which receives certain specific items, will prepare by printing, hectographing or otherwise, as many copies of the report cards as there are customers to be served. For each current subject a master control card is prepared by punching holes at specific locations on the card, each location corresponding to a particular receptacle of the machine, which receptacle is, in turn, assigned to a particular customer. For convenience the receptacles are numbered and the customers are designated by corresponding numbers. For example, receptacle No. 156 may be for John Smith & Co.

The master control card, having been punched with as many holes, each properly positioned, as there are customers to receive the particular report cards which have been printed, is placed in its proper position in the machine. The report cards are then fed to the machine, one by one, either by hand or automatically. The first card is promptly delivered to the first receptacle corresponding to the first punched hole in the master control card, which may be, for example, number three and the distributor carriage then immediately and automatically advances to the receptacle corresponding to the next succeeding punched hole in the master control card.

This series of successive operations is repeated until all cards are distributed to their proper receptacles. After the delivery of the final card the distributor carriage automatically returns to the starting point. If there happens to be a shortage of cards, not enough to supply one to each receptacle represented by a punched hole in the master control card, then in that case, the traveling distributor carriage does not automatically return to the starting point, thus directing attention to the shortage of cards. Or, if there happens to be a surplus of cards, the return of the carriage before the delivery of the last card indicates that fact.

Another common and useful application of the machine is for assembling or collating the leaves of a book or price list, or catalog composed of separate single sheets or of folded parts consisting of several pages. A simple lever movement as will hereinafter be made clear, connects all contact points corresponding to all re-

ceptacles of the machine without the use of any master control card. Under this condition each successive leaf of the book fed to the machine is delivered to each receptacle in succession until all are served and the carriage is returned to the starting point. The next leaf of the book, and succeeding leaves, are distributed in the same manner until the entire book is assembled.

Other useful applications of the invention will suggest themselves to one who works with the invention.

In the accompanying drawings I show one embodiment of the invention by way of example, but I wish it to be understood that there may be numerous deviations therefrom without departing from the spirit of the invention as defined in the appended claims.

Of the drawings—

Fig. 1 is a side view of the distributing machine minus certain parts and assemblies which are shown separately in other figures.

Fig. 2 is a side view of the distributor carriage.

Fig. 3 is vertical section through the distributor carriage along the line A—A of Fig. 4.

Fig. 4 is a plan view of the distributor carriage.

Fig. 5 is an end view of the distributor carriage partly in section along the line B—B of Fig. 3 and of the carriage track and a receptacle.

Fig. 6 is a wiring diagram and detail of the control box.

Fig. 7 is a detail of a tier of receptacles viewed transversely of the machine.

Fig. 8 is a side view of the tier of receptacles shown in Fig. 7.

Fig. 9 is a master control card.

In all drawings similar characters indicate the same or similar parts or objects and arrows indicate the direction of movement, travel or rotation.

The machine as shown in the exemplary embodiment of the drawings, is composed chiefly of a conveying mechanism, a traveling distributor carriage, a selective distribution control mechanism and tiers of receptacles.

The particular simple embodiment shown in the drawings is adapted to be placed with one side against a wall, from which it may be supported or to which it may be attached or braced.

A back plate 16 serves as the main support and carries the various parts attached thereto.

Conveying mechanism.—A motor 11 drives by means of the belt 12 and pulley 13 the double cord belt conveyor 14 which is driven by pulleys 15 and travels successively over idlers 16, 17, 18, 19 and 20 and the grooved rollers 21 and 22, thence over guide idlers 23, 24, 25, and 26, and thence back to the driving pulleys 15. These two cords 14 constitute the bottom or under pair of a three-cord conveyor, two of which are below the article carried and spread apart, and the third constitutes the upper run located midway between the two lower runs. Between the lower and upper runs the card or other object to be conveyed is carried. The top conveyor cord 31 is driven by the pulley 32 which in turn is driven by motor 11 through belt 12, pulley 33, belt 34, and pulley 35. Conveyor cord 31 travels successively over guide idlers 36, 38, 39, 20 and 21, the grooved roller 22, idlers 37, 38, 39 and 40 and thence back over its driving pulley 32. These three cords carry the cards being distributed from the receiving point at E to the point of discharge from the distributor carriage at F where the card enters the passage leading to its destined receptacle.

Traveling distributor.—As shown in detail in

Figs. 2, 3, 4, and 5, the carriage is adapted to be drawn along the angle supports 50 and 51 which extend along both sides of the machine. To these two supports are attached guide angles 52 and 53 and a third guide strip 54 is attached to support 50. The strip 54 serves the dual purpose of a guide for the carriage and as a ratchet stop. Its upper surface is provided with teeth 54a adapted to engage the pawl 71, as will hereinafter appear.

Shoes 55 on the base of the carriage slide freely on supports 50 and 51 and between guides 53 and 54. The carriage is drawn in either direction along its supports by cable 56 as shown in Fig. 6 by power furnished by motor 57 operating through a combined reduction gear and reversing clutch 58 of conventional design. When the carriage G has traveled to the limit of its movement away from the feed end of the machine it strikes a lever 59 which moves the rod 60 leading to the reversing clutch in gear box 58 and, by reversing the clutch effects the return of the carriage G to the feed end or starting point. There the carriage strikes the lever 61, again reversing the clutch in the gear box 58 but the immediate forward travel of the carriage is prevented by the engagement of the hooked lever 62 with the pin 63 which engagement can only be terminated by energizing magnet 64 to act upon the end of the hooked lever 62. The motor 57 and driving gear 58 are operated continuously by permitting the cable 56 to slip on pulley 65.

On the side of the carriage G is mounted a pair of opposed magnets 70 and 70a adapted to control the movement of one end of the pivoted pawl 71, the other end of which is adapted to engage the teeth 54a on the bar 54. Within the body of the carriage G is a rotatable contact disc 72 having a pin 73 projecting into and beyond the path of travel of objects being distributed, the passage of which cause the rotation of the disc 72 as will later appear. Attached to the contact disc 72 is a plate 74 adapted to simultaneously contact the points 75 and 76 upon rotation of the disc 72 caused by a passing card striking the pin 73. Counterweight 77 and spring 78 return the disc 72 to its normal position.

Bracketed to the side of the carriage G is a contact finger 78 adapted to contact segments 101 as will appear.

Extending through the base plate of the carriage G and transversely of the carriage is a discharge slot F adapted to direct the travel of the cards or other articles being distributed to the receptacles.

Selective distribution control mechanism.—Mounted on the side of the machine at the feed end is the mechanism H shown in detail in Fig. 6. A slab 81 of non-conducting material is provided with pockets 82, in number equal to the number of receptacles provided for the reception of distributed articles.

In the bottom of each pocket 82 is a plate 83 connected to a wire 84. Within each pocket, in contact with plates 83 is a small quantity of mercury 85. Above the slab 81 are mounted two parallel plates 86 and 87, spaced apart and moveable vertically by means of the cam 88 actuated by the lever 89, whereby the plates 86 and 87 may be raised or lowered. Plates 86 and 87 are provided with holes spaced to correspond with pockets 82 in slab 81, and are adapted to receive rods 90 each of which is provided with a stationary collar 91 and a spring 92 whereby rods

are held in their down position unless forced up against compression of the spring 92.

The upper surface of the slab 81 is adapted to receive a punched master control card such as is shown in Fig. 9. The holes in this card are so located that they accurately center on such of the rods 90 as correspond to certain receptacles as will later appear. Mounted along the guide angle 52 is a series of alternate contact segments 101 and insulating spacers 102. Each contact segment corresponds to a receptacle and are adapted to contact the finger 79 as the carriage G travels along its course.

Receptacles.—Arranged below the track upon which the carriage G travels are tiers of receptacles 110, arranged in nearly vertical banks. In the example chosen for illustration four receptacles are shown in each tier in Fig. 1 but there may be a greater or a lesser number as desired. The slight inclination of the tiers of receptacles causes the cards to come to rest in an inclined and compact position leaning against the back of the receptacle. One such card 111 is shown resting in a receptacle in Fig. 3. Across the top of each tier of receptacles are cross bars 112 which divide the width of the opening at the top of each tier of receptacles into as many equal parts as there are receptacles in each tier, in the present instance four.

The tiers of receptacles are formed by the slightly inclined partitions 113, the back plate 10, which is the back plate of the machine, and bottom shelves 114 which do not extend the entire distance from one partition to the next except at the bottom of the tiers 114a which is continuous.

From each of the bars 112 there extend pairs of small wire guides 115, shown in detail in Figs. 7 and 8, terminating in holes in each of the shelves 114 of each of the receptacles except the bottom receptacle of each tier. An additional pair of wire guides 116 serves the top receptacle of each tier. An offset 117 at the bottom of each of the wire guides serves to deflect the falling card toward the opposite side of the receptacle, thus providing room for the succeeding cards.

At the rear of each receptacle is a small block 118, which may be of rubber, upon which one corner of the cards rest. Across the open fronts of receptacles of each tier and above their middle, are provided rods 121 the ends of which are attached to cables 122 which pass over sheaves 123 and are attached to one end of lever 124, by the movement of which all of the rods 121 may be raised or lowered in unison.

As the cards fall into their respective receptacles they come to rest in a slightly inclined position leaning against the inclined side of the receptacle, as shown by the card 111a in Fig. 5, and with one bottom corner resting on the block 118 and with one edge against the rod 121 in its upper position. When the rods 121 are lowered by movement of the lever 124 to their lowest position the cards in all receptacles will tip outwardly to the position shown by card 111b in Fig. 5. From this position all cards are visible to the operator and are easily accessible for removal from the receptacle.

Master control card.—The control of the movements of the distributor carriage is centered in the control box, the details of which are shown in Fig. 6, but the master control is vested in a punched card which is prepared in advance for each job of distribution. An example of such a master control card is shown in Fig. 9. This

master card is punched in a suitable punching machine which forms no part of the present invention. The location of the holes in the card corresponds accurately with the location of the pins 90 in the control box H which in turn correspond with the receptacles 110. For example, a hole at 131 on the control card may be designated No. 1 and would correspond with pin number one in control box H which in turn corresponds to receptacle number one in the bank of receptacles. If the machine has four hundred receptacles for cards there would be four hundred pins in the control box H and four hundred positions for holes on the master control card, which might conveniently be arranged in twenty rows with twenty positions in each row.

For each distribution operation a master control card is punched with a hole at each position representing each receptacle which is to receive a card, of which there may be any number from one to the full limit of the machine. When a control card so prepared is placed in registered position in the control box H on top of the slab 81 as shown at J in Fig. 6, and the lever 89 manipulated to lower the plates 86 and 87 lowering the pins 90 against the card, certain of the pins 90, namely all of those which register with holes punched in the card, will pass through those holes, enter the pockets 82 and come into contact with the mercury in the bottom of the pockets. Thus electrical contacts will be established between the plates 86 and 87 and each of the circuits, 156 corresponding to each hole in the punched card. In Fig. 6 the pins 141 and 142 are shown passing through holes in the punched card J and in contact with the mercury 85 in the bottom of the pockets 82 while other pins are shown retained on the card as they were lowered by the operation of the lever 89.

Electric circuits.—The wiring plan of the electric circuits which serve to control the movements of the mechanism while in action, except the feeding of the cards or other articles being distributed, is as follows; a source of electric energy, indicated in Fig. 6 as a battery 151 is connected by circuit 152 to one pole of a contact 153 the other pole of which is mounted on the plate 87 so that when plate 87 is elevated by lever 89 the circuit is broken and when plate 87 is lowered contact is established, resulting in energizing magnet 64 through circuit 152 and releasing the distributing carriage G from the hook 62.

Battery 151 is also connected to plate 87 through flexible connection by circuit 154 which also connects magnet 70 with contact point 76 and, when, by the passage of a card causes the pin 13 to rotate the disc 72 and bring contact plate 74 into contact with contact points 75 and 76 the magnet 70 becomes energized and lifts the rocker arm 71 from the tooth 54a permitting carriage G to be advanced to its next station. Through circuit 154 current is supplied to all of the pins 90 and through such of the pins as are in contact with the mercury in the bottom of pockets 82 with corresponding segments 101 through their connecting wires 156. Through contact segments 101 circuit 156 is completed when contact finger 79 passes over its surface, energizing magnet 70a causing rocker arm 71 to engage tooth 54a which is then in position to receive it.

The operation of the machine proceeds as follows; it is assumed that cards are to be distributed to receptacles 3, 9, and 24, it being understood that the number of receptacles to which

cards may be distributed is limited only by the number of receptacles. A master card is first punched in the positions corresponding to pins numbers 3, 9, and 21. The punched card is placed in registry with the pins in the control box H on top of slab 81. The distributor carriage is at its starting position with the hook 62 engaging the pin 63. The lever 89 is manipulated to depress the plates 86 and 87 carrying the pins 90 into contact with the card while the pins three, nine and twenty-one pass through the previously punched holes and into contact with the mercury in pockets 82, thus placing these pins in electrical connection with the third, ninth and twenty-first contact blocks 101. Motors 11 and 57 are then started which puts in motion conveyor cords 14 and 31 while cable 56 remains stationary but slipping on its drive pulley within the gear box 58. The contact 153 having been closed, momentarily energizing magnet 64 and so releasing carriage G it moves forward under the pull of cable 56 until the contact finger 79 on the side of the carriage, comes in contact with the third contact bar 101. This energizes magnet 70a, throws arm 71 into position to engage with tooth 54a and stops the carriage with the chute F centered over the entrance to the passage leading to receptacle number three. The machine is now ready to receive and distribute cards continuously.

When the first card is fed to the conveyor at the point E it is carried speedily by the cord conveyor to the entrance to the distributor carriage G at the grooved roller 22, where the two lower cords 14 are spread apart to the sheaves 23 off to either side of, and away from the card, permitting the card to pass between the cords 14 and to be guided by the cord 31 and rollers 37 and 38 to the chute F, Fig. 3, which is positioned directly over the opening between bars 112 corresponding to the third receptacle to which the first card is to be delivered.

In traveling to the chute F the card has, on its way, moved pin 73 which rotated disc 72 and brought the contact plate 74 against point 75 and 76 closing circuit 154, energizing magnet 70 which lifts rocker arm 71 from engagement with tooth 54a and permits the carriage G to be drawn along its track until contact finger 79 moves to the next contact bar 101 which is in electrical circuit with one of the pins 90. In the example it would be pin number nine.

In the meantime, the first card having been delivered to the guides leading to receptacle and released, falls between and is guided by guide wires 115, two on each side of the card, and extending from the bars 112 to the edge of the shelf 114 forming the bottom of the receptacle. As the card hits the offset 117 at the lower end of the guide wires it is deflected toward the opposite side of the receptacle and comes to rest leaning against the side of the receptacle opposite the guide wires and with one lower corner resting on the block 118 and with its diagonally opposite upper corner against the rod 121.

While this is taking place, a second card has been fed to the conveyor, the carriage had already advanced until stopped with the chute F directly over the entrance to the passage leading to receptacle number nine by reason of the contact finger 79 having passed over the contact bar 101 corresponding to receptacle number nine causing magnet 70 to become energized throwing arm 71 into engagement with a tooth 54a.

As this second card, in passing through the carriage, rotated the contact disc 72 by striking and

deflecting the pin 73 the same chain of events has taken place and while the second card is falling into receptacle number nine, the carriage is moving forward to the chute leading to receptacle twenty-one and is ready to receive the third card and guide it to its destination. Thus each card, as it passes through the carriage G, sets up a train of events that cause the carriage to advance and to stop at the entrance to next receptacle corresponding to which there is a hole punched in the master control card then in the control box. When the last card has been delivered, the last stop has been made, and there are no more contact bars 101 in circuit to cause the carriage to stop, it will continue to travel until it moves lever 59 and so reverses the clutch in the gear box 58 and causes the carriage to return to its starting point where, by moving the lever 61 it will again reverse the clutch but will be prevented from moving by the automatic engagement of the hook 62 with the pin 63.

All cards having been distributed, the lever 124 is manipulated to lower the rods 121 from the upper to the lower part of the receptacles. Whereupon all of the cards in all of the receptacles will tilt forward from the position of the card 111a, Fig. 5, to the position of card 111b, in which position the upper corner of all cards project beyond the front of the receptacles and become plainly visible to the operator who then does not have to search all of the four hundred receptacles to ascertain which of them contain cards.

Having completed the distribution and removal of the cards the master control card is removed and another substituted for the next group of cards to be distributed.

When used for assembling the pages of a book or the like, no master control card is required. By manipulation of the lever 89 all of the pins 90 are lowered into the pockets 82 and into contact with the mercury 85 therein. This places all of the contact bars 101 in circuit so that the carriage G will stop at each receptacle in succession and one sheet will be delivered to each of them.

Having described my invention and disclosed one of the preferred forms in which it may be put into practice by one skilled in the art to which it pertains, I now state what I believe to be new and novel and for which I pray that Letters Patent be granted.

I claim—

1. A distributing machine comprising, in combination, a conveying means adapted to receive objects to be distributed, to move them from a receiving station to a plurality of points of release from said conveying means, means movable over all of said points of release for releasing said objects from said conveying means, control means, external of the articles distributed, adapted to selectively determine the points of release of the articles from the conveying means, a plurality of receptacles disposed in a plurality of nearly vertical tiers, each tier comprising a plurality of receptacles and having guided passages leading from the points of release along one side of said tiers of receptacles to each of the receptacles in the tier, means governed by said control means for selectively and successively registering said points of release from said conveying means with the entrance to the selected guided passages to such of the receptacles as have been set up in the said control means.

2. In a distributing machine, the combination of a conveying means adapted to receive and to convey a succession of similar articles from a

source of supply and to deliver each of them to one of a plurality of discharge stations, means movable over all of said discharge stations for releasing said objects from said conveying means and means separate from the articles distributed adapted to automatically pre-select the particular station to which each of said articles is to be delivered by said conveying means.

3. In a distributing machine, the combination of a conveying means adapted to receive and to convey a succession of similar articles from a source of supply and to deliver them to a bank of receptacles comprising a plurality of nearly vertical tiers of receptacles, each tier being composed of a plurality of receptacles, the receptacles of each tier having a common member forming one side of the tier, the bottom of each receptacle being at a right angle with the nearly vertical side member, thus forming a sloping shelf upon which the distributed articles may rest, said shelf being of a width less than the distance between the back members of adjacent tiers of receptacles, the open fronts of all receptacles being traversed by a horizontal movable bar adapted to be held at a point above the middle of the horizontal rows of receptacles and to be lowered to a point below the middle of the said rows of receptacles, a plurality of passages, equal in number to the number of receptacles in each tier, defined by bars extending across the top of the uppermost receptacle of each tier and by a plurality of yielding guides, each attached to said bars, each extending along one side of the tier of receptacles to the bottom shelf of the receptacle it serves and each provided at its lower end with an offset toward the opposite side of the receptacle it serves, means separate from the articles distributed adapted to automatically select the stations to which said articles are delivered by said conveying means.

4. A distributing machine comprising, in combination, a conveying means adapted to receive articles to be distributed, to move them from a receiving station to each of a plurality of points of release from said conveying means, means to release said articles from said conveying means, control means, external of the articles distributed, adapted to selectively determine the plurality of points of release of the articles from the conveying means and to stop and start said releasing means at said point of release, said control means including a master control card having apertures therethrough, adapted to be positioned in registry with movable electrical contact members whereby selective electrical control over the movement of said conveying means is established by such of said contact members as, by reason of their registry with said apertures, are in position to make contacts through them, a plurality of receptacles disposed in a plurality of nearly vertical tiers, each tier comprising a plurality of receptacles and having guided passages leading from the points of release along one side of said tiers of receptacles to each of the receptacles in the tier, means governed by said control means for selectively and successively registering said points of release from said conveying means with the entrance to the selected guided passages leading to such of the receptacles as have been set up in said control means.

5. A distributing machine comprising in combination, a conveying means adapted to receive articles to be distributed, to move them from a receiving station to each of a plurality of points of release from said conveying means, means to release said articles from said conveying means,

control means, external of the articles distributed, adapted to selectively determine the plurality of points of release of the articles from the conveying means and to stop and start said releasing means at said points of release, said control means including a master control card having apertures therethrough, adapted to be positioned in registry with movable electrical contact members, whereby selective electrical control over the movement of said conveying means is established by such of said contact members as, by reason of their registry with said apertures, are in position to make contacts through them, a plurality of receptacles disposed in a plurality of nearly vertical tiers, each tier comprising a plurality of receptacles and having guided passages leading from the points of release along one side of each tier of receptacles to each of the receptacles in the tier, means governed by said control means, for selectively and successively registering said points of release from said conveying means with the entrance to the selected guided passages to such of the receptacles as have been previously set up in said control means.

6. In a distributing machine, the combination of a plurality of nearly vertical tiers of receptacles, each tier comprising a plurality of receptacles, a plurality of guided passages, equal in number to the total number of receptacles and each having equally spaced entrance openings in a plane substantially horizontal, extending above the tiers of receptacles, conveying means positioned over said passages adapted to receive a succession of identical articles from a source of supply and to convey said articles from said source to a conveyor discharge means adapted to discharge said articles into said guided passages, and control means for selectively determining the passages to which said conveyor discharges said articles, means for controlling the movement of the conveyor discharge means which includes a plurality of electrical contact bars interspersed with insulating bars, said contact bars being equal in number to the number of stations at which it is desired to stop the said conveyor discharge means, and each positioned in uniform relation with said stations, a contact member supported by, and moveable with, said conveyor discharge means and adapted to be moved successively into and out of contact with said bars by the movement of said conveyor discharge means, said controlling means also including a master control card having apertures therethrough adapted to be positioned in registry with movable electrical contact members whereby selective electrical control over the movement of said conveying means is established by such of said contact members as, by reason of their registry with said apertures, are in position to make contacts through them.

7. In a distributing machine, the combination of a plurality of nearly vertical tiers of receptacles, each tier comprising a plurality of receptacles, a plurality of nearly vertical guided passages, equal in number to the total number of receptacles and each having equally spaced entrance openings in a single plane substantially horizontal, extending above the tiers of receptacles, conveying means positioned over said passages adapted to receive a succession of identical articles from a source of supply and to convey said articles from said source, a conveyor discharge means adapted to discharge said articles into said guided passages, and control means for selectively determining the passages

to which said conveyor discharges said articles, means within each of said receptacles adapted to cause the articles deposited therein to incline toward the front of the receptacle, a movable bar positioned across the front of said receptacles and adapted to confine the articles within said receptacles, means for repositioning said bars to permit said articles to tilt forward and project beyond the front of said receptacles, said control means including a master control card having apertures therethrough adapted to be positioned in registry with selective contact means including a plurality of collectively and individually movable electrical contact members in symmetrical arrangement positioned in registry with an equal number of stationary electrical contacts and adapted to be brought into contact either collectively or selectively by the interposition of said master control card between said stationary and said moveable contact members, and means for controlling the movement of said conveyor discharge means including a plurality of electrical contact bars disposed along the path of travel of said conveyor discharge means and interspaced with insulating bars, said contact bars being equal in number to the stations at which it is desired to stop the said conveyor discharge means, and each positioned in uniform relation with said stations, a contact member supported by, and moveable with, said conveyor discharge means and adapted to be moved successively into and out of contact with said bars by the movement of said conveyor discharge means.

8. A distributing machine characterized by having a conveyor comprising a plurality of flexible strands adapted to be disposed on opposite sides of and in contact with the articles distributed, traveling means for discharging from the conveyor the articles distributed, including means for spreading the strands in contact with the lower side of the said articles to a distance apart greater than the corresponding dimension of the articles distributed, permitting said articles to pass between the spread-apart strands, said traveling conveyor discharge being propelled from a source of power which delivers its energy through driving pulleys over which a belt is permitted to slip when the traveling conveyor discharge is not in motion, means for arresting the forward motion of the conveyor discharge means including a toothed rack positioned along the path of travel of the conveyor discharge means, a pivoted pawl carried by said conveyor discharge means adapted to be engaged with the teeth on said rack, said teeth being accurately positioned with reference to, and of equal number to, the stations at which it is desired to stop said conveyor discharge means, means for causing said pawl to engage teeth on said rack as the conveyor discharge means reaches each station at which an article is discharged from said conveyor.

9. A distributing machine distinguished by a plurality of tiers of receptacles for the articles distributed, each tier comprising a plurality of receptacles, guiding means adapted to direct the travel of the articles from the point of entry at the top of each tier to each of the receptacles comprising the tier, said guiding means comprising spaced-apart bars across the top of the up-

permost receptacle of each tier, thin flexible guide members attached to each of said cross bars and extending downwardly and terminating at the bottom of the receptacle to which it serves as a guide, means within each receptacle adapted to cause the articles deposited therein to incline toward the front of said receptacle, a moveable bar positioned across the front of said receptacles and adapted to confine the articles within said receptacles, means for repositioning said bars to permit said articles to tilt forward and project beyond the front of said receptacles, and conveying means adapted to convey articles selectively to said guiding means.

10. In a distributing machine, the combination of a conveying means adapted to receive and to convey successive similar articles from a source of supply and to deliver them to a plurality of discharge stations, means separate from and unrelated to, the articles distributed, adapted to automatically control the stations to which said articles are delivered by said conveying means, said conveyor comprising a plurality of flexible strands disposed on opposite sides of, and in contact with, the articles distributed, means for discharging from the conveyor the articles distributed, including means for spreading the strands in contact with the lower side of the said articles to a distance apart greater than the corresponding dimension of the articles distributed, permitting said articles to pass between said spread-apart strands.

11. In a distributing machine, the combination of a plurality of nearly vertical tiers of receptacles, each tier comprising a plurality of receptacles, a plurality of guided passages, equal in number to the total number of receptacles and each having equally spaced entrance openings in a single plane substantially horizontal, conveying means positioned above the tiers of receptacles, adapted to receive a succession of identical articles from a source of supply of said articles and to convey said articles from said source, a conveyor discharge means adapted to travel over said tiers of receptacles and to discharge said articles successively in a downward direction into said guided passages, and control means, which is separate from the articles distributed, adapted to selectively predetermine the passages to which said conveyor discharges said articles, means for arresting the forward movement of said traveling conveyor discharge means, including a toothed rack positioned along the path of travel of the conveyor discharge means, a pivoted pawl carried by said conveyor discharge means, said pawl being adapted to be engaged with the teeth of said rack, said teeth being equal in number of guided passages at which it is desired to stop said conveyor discharge means and uniformly positioned with reference thereto, means for causing said pawl to engage successive teeth on said rack as the conveyor discharge means reaches each station at which an article is to be discharged from said conveyor, means located at either end of its travel, actuated by the movement of the conveyor discharge means, for reversing the direction of travel, whereby said conveyor discharge means is returned to its starting position.
